UNITED STATES PATENT OFFICE.

MINNIE WILBOR BOARD, OF ELMA, NEW YORK.

DESIGN FOR A UTENSIL-STAND.

51,055.

Specification for Design.

Patented July 24, 1917.

Application filed May 2, 1916. Serial No. 94,999. Term of patent 14 years.

To all whom it may concern:

Be it known that I, MINNIE WILBOR BOARD, a citizen of the United States, residing at Elma, in the county of Erie and State of New York, have invented a new, original, and ornamental Design for Utensil-Stands, of which the following is a specification.

The accompanying drawing is a perspective view of a utensil stand embodying this design.

The design comprises parallel vertical corner rods or standards connected between

their upper and lower extremities by cross bars disposed in triangular relation, and circular horizontal shelves, confined between the corner standards.

I claim—

The ornamental design for a utensil stand, as shown and described.

MINNIE WILBOR BOARD.
